(57) **CLAIM**

The ornamental design for a kegel exercise monitoring device, as shown and described.

DESCRIPTION

FIG. 1 is a side perspective view of a kegel exercise monitoring device showing the new design;

FIG. 2 is a right side elevation view thereof, the left side being a mirror image thereof;

FIG. 3 is a front view thereof;

FIG. 4 is a top view thereof;

FIG. 5 is a bottom view thereof; and,

FIG. 6 is a rear view thereof.

The thin discontinuous lines shown in the Figures represent surface contour and shading.
